UNITED STATES PATENT OFFICE.

HENRY HANSBERGER, OF MILLERSPORT, OHIO.

FENCE-POST.

SPECIFICATION forming part of Letters Patent No. 748,946, dated January 5, 1904.

Application filed May 13, 1902. Serial No. 107,112. (No model.)

To all whom it may concern:

Be it known that I, HENRY HANSBERGER, a citizen of the United States, residing at Millersport, in the county of Fairfield and State 5 of Ohio, have invented a certain new and useful Improvement in Fence-Posts, of which the following is a specification.

My invention relates to the improvement of fence-posts; and the objects of my invention are to provide a substantial and durable fence-post and base therefor of improved construction and arrangement of parts, to so construct and arrange said base and post as to insure the retention of the post in a vertical 10 position, and to produce the same of simple and inexpensive construction. These objects I accomplish in the manner illustrated in the accompanying drawings, in which—

Figure 1 is a view in elevation of my improved post-base and a portion of the post connected therewith, the same being shown in connection with the ground; and Fig. 2 is a central vertical section of the same.

Similar numerals refer to similar parts throughout both views.

In carrying out my invention I mold or otherwise construct of cement an upright fence-post base or support 1, the latter having its lower end portion flanged laterally, as indicated at 2. The body of said post base or support may, as indicated in the drawings, be tapering toward its upper end or otherwise suitably shaped. In forming my improved base it is made to inclose while in a plastic mass the lower portion of a central and vertical post 3, which is preferably of metal. In order to insure the connection of the lower portion of the post 3 with the body of the base 1, I provide a transverse opening 35 in the lower portion of said post, through which extends a horizontal pin 4, the latter being, as prescribed for the lower portion of the post, incased by the material forming the base. The outwardly-projecting portion of the post 3 may, as indicated at 5, be formed with suitable openings or other means for connecting wires or other post-connecting parts therewith. As indicated in the drawings, the upper end portion of the base-body

1 is adapted to be incased or surrounded by 50 a horizontally-disposed cement block 6, the central opening of which may conform to the outline of the upper portion of said base.

In Fig. 1 of the drawings I have shown my improved base and a portion of the post rising therefrom, said post being embedded in the earth, which is indicated in section at 7. From this illustration it will be seen that the top block 6 and the upper end of the base-body 1 are designed to be flush with each other 60 and with the ground-surface.

From the construction shown and described it will readily be understood that the earth which bears upon the upper side of the base-flange 2 and about the body of said base will 65 serve to hold the latter firmly in connection with the ground and that the top block 6, being, as shown, sunk to the depth of its body in the ground, any tendency of the upper portion of the base to be moved from its 70 vertical position will be obviated, with the result that the post will be maintained at all times rigid. It is obvious that any tendency of the post to become sufficiently loose within the base 1 to admit of its being withdrawn 75 therefrom will be obviated by the employment of the cross locking-pin 4, which is embedded in the lower portion of said base in the manner heretofore described.

Having now fully described my invention, 80 what I claim, and desire to secure by Letters Patent, is—

In a fence-post, the combination with a base 1 comprising a solid body of cement flaring toward its lower end and formed with a base-flange, of a post extending centrally through said base-body, a transverse pin 4 intersecting said post and having its ends inclosed within the base-body and a separately-formed horizontally-disposed block having a central 85 opening therein adapted to receive the upper end of the base-body and having its upper side 90 flush therewith, substantially as specified.

HENRY HANSBERGER.

In presence of—

C. C. SHEPHERD,
P. S. KARSHNER.
